CONVEYOR

Charles N. Hannon, Olathe, Kans., assignor to Warren W. Hannon, Olathe, Kans.

Filed Apr. 12, 1971, Ser. No. 133,455

Term of patent 14 years

Int. Cl. D15—03

U.S. Cl. D55—1

Fig. 1.

Fig. 2.

Fig. 3.

FIG. 1 is a front corner perspective view of a conveyor embodying my new design;

FIG. 2 is a plan thereof; and,

FIG. 3 is another corner perspective view of the conveyor with the sides of the inclined conveyor portion illustrated in the position thereof folded down flat and the lower side panels removed.

I claim:

The ornamental design for a conveyor, as shown and described.
